UNITED STATES PATENT OFFICE.

JOSEPH F. DELCOURT, OF NEW BEDFORD, MASSACHUSETTS.

CLASP.

1,377,116.

Specification of Letters Patent.

Patented May 3, 1921.

Application filed August 20, 1920. Serial No. 404,893.

To all whom it may concern:

Be it known that I, JOSEPH F. DELCOURT, a citizen of the United States, residing at New Bedford, in the county of Bristol and 5 State of Massachusetts, have invented certain new and useful Improvements in Clasps; and I do declare the following to be a full, clear, and exact description of the invention, such as will enable others skilled 10 in the art to which it appertains to make and use the same.

This invention relates to improvements in clasps, more particularly to clasps for garments such as waist-bands of drawers, garments 15 etc.; and its object is to provide a simple and practical device of this character which will be very effective in operation.

Another object of the invention is to so 20 construct the stationary jaw that it may have an extension forming a resilient carrying arm for the movable jaw and actuating mechanism thus providing resilient means for holding the movable jaw in tight 25 engagement with the stationary jaw when moved to an operative position.

Another object of the invention is to so 30 construct the stationary jaw and movable jaw that a firm grip upon the material placed between the jaws may be obtained, and tearing of the material prevented.

Another object of the invention is to so 35 construct the operating lever and movable jaw that the movable jaw may be mounted upon an eccentric disk carried by and moving with the operating lever.

This invention is illustrated in the accompanying drawings, wherein:

Figure 1 is a perspective view of the im- 40 proved clasp showing the same in the inoperative position.

Fig. 2 is a view similar to Fig. 1 showing the movable jaw swung to the operative position.

Fig. 3 is an enlarged longitudinal sec- 45 tional view through the clasp with the movable jaw in the inoperative position.

Fig. 4 is a similar view showing the clasp with the movable jaw in the operative posi- 50 tion.

Fig. 5 is a sectional view taken along the line 5—5 of Fig. 4.

Fig. 6 is a sectional view taken along the line 6—6 of Fig. 4.

Fig. 7 is a group view showing the various elements of the clasp in perspective.

Fig. 8 is a view similar to Fig. 4 showing a slightly modified construction.

Fig. 9 is a perspective view of a movable jaw showing a slightly modified construc- 60 tion from that disclosed in Fig. 7.

This clasp will be used for engaging a garment and is so constructed that it may be slipped over the edge of a waist-band and the movable jaw then brought into the operative position so that the waist-band 1 will be tightly gripped between the two jaws 2 and 3 as shown in Fig. 6. From an inspection of Figs. 3 and 4, it will be seen that when moved to the operative position, the 70 movable jaw is first swung into engagement with the stationary jaw and as the actuating lever is forced down to the position of Fig. 4, the movable jaw will be moved longitudinally of the stationary jaw and the 75 resilient tongue of the movable jaw will be forced away from the same thus providing the necessary pressure to hold the movable jaw in tight engagement with the stationary jaw and further providing the necessary 80 pressure which will serve to prevent the lever from returning to the position of Fig. 1 and thus releasing the clasp.

In the form shown in Figs. 1 through 7, the device is intended for use in connection 85 with a waist-band and two of the clasps will be carried by a connecting strip of yieldable material but it is to be understood that the clasp may be used in any connection where a clasp of this character may be used. 90

Referring to Fig. 7 which discloses a group view of the principal elements forming this clasp, it will be seen that the clasp is provided with a stationary jaw 2, a movable jaw 3, an actuating lever 4 and a cam disk 5. The stationary jaw 2 is formed from a strip of resilient metal cut to provide longitudinally extending grooves or seats 6 and bent intermediate its length to provide an overhanging arm 7 which is cut 100 from its free end thus providing spaced fingers 8 rolled to form the bearings 9. Since the stationary jaw is formed of resilient metal, the overhanging arm 7 may have movement toward and away from the movable jaw thus providing the necessary pressure when the movable jaw is moved toward the stationary jaw.

The movable jaw 3 is formed with side members 10 each of which is formed from 110 a blank of sheet metal bent longitudinally and connected by rivets 11 to provide an

upstanding rib 12 having an opening 13 formed therein. The side wings of this movable jaw are crimped longitudinally so that the jaw will fit into the seats 6 of the 5 stationary jaw as shown in Fig. 6 and this movable jaw is of greater width than the stationary jaw and has one side portion extending outwardly from the side of the stationary jaw and cut to provide a longitudinally 10 extending slot 14. In the form shown in Figs. 2 and 7, the second side portion is bent down to form a depending lip 15 for clamping the material 1 against the side of the stationary jaw as shown in Fig. 15 1 but in the form shown in Fig. 9, the second side of this movable jaw extends outwardly similar to the side having the slot 14 and is provided with a slot 16, the tongue 17 formed when cutting this slot being bent 20 down to provide a tongue corresponding to the tongue 15. It will thus be seen that with the form shown in Fig. 2, a strip of fabric for connecting two of the clasps can only be connected with one side of a clasp 25 whereas in the form shown in Fig. 9, the connecting strip could be connected with either side of a clasp. The structure shown in Fig. 8 is similar to that disclosed in Fig. 4 except that one of the side wings of the 30 movable jaw is provided with a tongue extension bent to form an eye 18 in which a key-ring or other similar device may be placed.

The actuating lever 4 is formed from a 35 strip of sheet metal which is bent intermediate its length thus providing side arms 19 which will extend upon opposite sides of the rib 12 when the lever is put in place as shown in Fig. 1. This lever has its arms 19 40 provided with openings 20 to receive a pin 21 which passes through an opening 22 formed in the eccentric disk 5 which will be positioned in the opening 13 and the arms are provided with a second set of 45 openings 23 to receive a pivot pin 24 which is journaled in the bearings 9 and extends through these openings 23 and also through a cutout 25 formed in the eccentric disk 5 adjacent the periphery thereof. It will 50 thus be seen that when the lever is put in place and connected with the disk 5 by the pin 21 and the lever and disk mounted between the fingers 8 by means of the pivot pin 24, the lever will be pivotally mounted 55 and the movable jaw will be eccentrically mounted thus causing it to swing downwardly to engage the stationary jaw and then moved longitudinally of the stationary jaw when the lever is swung from the position of Fig. 1 to that of Fig. 2. It will 60 be further noted that when the lever is swung downwardly to the locking position, the pin 21 will move from a position to one side of the pin 24 past the dead center to a 65 position upon the opposite side of the pin

24 and therefore the resiliency of the arm 7 will serve not only as means to force the movable jaw into tight engagement with the material 1 but will further serve as means preventing the lever from accidentally swinging toward a releasing position. 70

When this device is in use, the jaws will be in the inoperative or releasing position shown in Fig. 1 and the material 1 can then be easily passed between the two jaws. 75 The lever will then be swung downwardly to the position of Fig. 2 but in doing so the movable jaw will first be brought into engagement with the material and then moved longitudinally of the jaw 2 and forced into 80 tight gripping engagement with the material. This will distort the material as shown in Fig. 6 and the material will be very firmly gripped thus preventing slipping of the clasp. The point of prong 26 85 is formed by punching the metal of one arm 9 and will fit into a socket or seat 27 formed in the rib 12 when the lever is swung down to the locking position. After the movable jaw has been brought into 90 gripping engagement with the fabric positioned between the two jaws, this fabric will be very firmly gripped and will not be liable to slip loose especially if the strain is transversely of the jaws. There has thus 95 been provided a clasp which can be easily and quickly put in place or removed and which will not be liable to slip loose when in place, nor to tear the material since the jaws have sufficient bearing surface upon 100 the latter. It will be seen that the movable jaw of the clasp is mounted for swinging movement on the eccentric disk so that it can swing or tilt and adapt itself to any irregularities in the material which is 105 placed between the jaws.

I claim:

1. A clasp comprising a stationary jaw formed from a strip of resilient material having one end portion bent to provide a 110 spring arm overhanging the stationary jaw, a movable jaw positioned between the stationary jaw and spring arm and having an upstanding rib provided with an opening, an actuating lever having spaced arms extending upon opposite sides of the rib of said movable jaw, a disk carried by the actuating arm and positioned in the opening of the rib to mount the rib for swinging movement upon the disk, and a pivot pin 115 carried by the spring arm and passing through aligned openings in the disk and arms of the actuating lever, the openings receiving the pivot pin being positioned adjacent the periphery of the disk to mount the 120 eccentric movement.

2. A clasp comprising a stationary jaw formed from a strip of resilient material having one end portion bent to provide an overhanging arm terminating in spaced fin- 130

gers, a movable jaw having an upstanding rib extending between the spaced fingers and provided with a circular opening, a disk positioned in the opening of the rib, an actuating lever extending between the fingers of the spring arm upon opposite sides of the rib, and a pivot pin journaled in bearings carried by the fingers and extending through openings formed in the side arms of said lever and through an opening formed adjacent the periphery of the disk to mount the disk for eccentric movement when the lever swings upon the pivot pin and moves the movable jaw toward and away from the stationary jaw and longitudinally of the stationary jaw when in engagement therewith.

3. A clasp comprising a stationary jaw, a spring arm extending above the stationary jaw, a movable jaw positioned between the stationary jaw and spring arm, a rib carried by the movable jaw and having a circular opening formed therein, a disk positioned in the opening of the rib, an actuating lever having spaced arms extending upon opposite sides of the rib and having said disk connected therewith, and a pivot pin carried by the spring arm and extending through openings in the disk and side arms of said lever to pivotally mount the lever, the opening in the disk receiving the pin being positioned adjacent the periphery thereof to mount the disk for eccentric movement when the lever is swung upon the pivot pin and move the movable jaw toward and away from the stationary jaw and longitudinally of the stationary jaw when in engagement therewith.

4. A clasp comprising a stationary jaw, a spring arm extending above the stationary jaw, a movable jaw positioned between the spring arm and stationary jaw, the stationary jaw having longitudinally extending grooves forming seats and the movable jaw being bent to conform to the contour of the stationary jaw and fit into the seats, a lever pivotally connected with the spring strip, a rib carried by the movable jaw and having an opening formed therein, and a disk carried by the lever for eccentric movement when the lever is swung pivotally and positioned in the opening of the rib to move the movable jaw toward and away from the stationary jaw and longitudinally thereof when in engagement with the stationary jaw.

5. A clasp comprising a stationary jaw, a movable jaw, a resilient support, an actuating lever pivotally connected with the support, and a disk connected with the lever and

having eccentric movement when the lever is swung upon its pivot, the disk fitting into an opening formed in a portion of the movable jaw to move the movable jaw toward and away from the stationary jaw and impart movement to the movable jaw longitudinally of the stationary jaw.

6. A clasp comprising a stationary jaw, a resilient supporting arm carried thereby and extending in spaced relation thereto, a movable jaw, an eccentric on which said movable jaw swings, a lever having loose connections with the eccentric for actuating the same, and a common pivot for the lever and eccentric.

7. A clasp comprising a stationary jaw, a movable jaw having a centrally arranged rib with a circular opening therein, an eccentric disk arranged in said opening, a pivotal support for the eccentric connected to said fixed jaw yieldably, and a lever for actuating the eccentric.

8. A clasp having a jaw, a yieldable support carried thereby and extending in overhanging relation to the same, a second jaw between the first jaw and support, an upstanding rib carried by the second jaw and having a circular seat formed therein, an actuating lever pivotally connected with said support for swinging movement against the side of said rib, and a circular disk carried by said lever eccentrically to its pivot and positioned in the seat of said rib for imparting movement to one jaw relative to the other when the lever is moved.

9. A clasp having a jaw, a second jaw having a longitudinally extending rib, a pivotally mounted actuating lever having eccentric connection with the second jaw for moving one jaw toward the other into contacting relation therewith and then longitudinally thereof into a locking position, and a latching stud carried by said rib for snapping into a socket of the lever and holding the lever in a locked position.

10. A clasp comprising a jaw, a second jaw, a yieldable support carried by the first jaw, and an actuating element pivotally connected with the support and having eccentric engagement with the second jaw for moving one jaw toward the other into contacting engagement therewith, and then longitudinally thereof to a locked position.

In testimony whereof I have hereunto set my hand.

JOSEPH F. DELCOURT.
